ROSARY

John Taylor, 3102 N. 6th Ave., Apt. A-111,
Phoenix, Ariz. 85013

Filed Apr. 21, 1969, Ser. No. 16,839

Term of patent 14 years

Int. Cl. D11—01

U.S. Cl. D45—16

FIG. 3

FIG. 2

FIG. 1

FIGURE 1 is an elevational view of the obverse side of a rosary, showing my new design;

FIGURE 2 is an elevational view of the reverse side thereof; and

FIGURE 3 is a cross-sectional view of the rosary taken along the lines 3—3 of FIGURE 2.

I claim:

The ornamental design for a rosary, as shown.

1,938,727 12/1933 Tammany.
2,033,943 3/1936 Lely.
